(57) CLAIM

The ornamental design for a fishing weight, as shown and described.

DESCRIPTION

FIG. 1 is a perspective view of a fishing weight of the present design;

FIG. 2 is a front elevation view of the design in FIG. 1;

FIG. 3 is a rear elevation view of the design in FIG. 1;

FIG. 4 is a side elevation view of the design in FIG. 1;

FIG. 5 is a second side elevation view of the design in FIG. 1;

FIG. 6 is a top plan view of the design in FIG. 1;

FIG. 7 is a bottom plan view of the design in FIG. 1;

FIG. 8 is a perspective view of an alternative embodiment of a fishing weight;

FIG. 9 is a front elevation view of the design in FIG. 8;

FIG. 10 is a rear elevation view of the design in FIG. 8;

FIG. 11 is a side elevation view of the design in FIG. 8;

FIG. 12 is a second side elevation view of the design in FIG. 8;

FIG. 13 is a top plan view of the design in FIG. 8; and,

FIG. 14 is a bottom plan view of the design in FIG. 8.
